UNITED STATES PATENT OFFICE.

GUSTAV E. FRITZ, OF PEORIA, ILLINOIS, ASSIGNOR TO UNIVERSAL INTERCHANGEABLE TOOTH COMPANY, OF PEORIA, ILLINOIS, A CORPORATION OF ILLINOIS.

BACKING-PLATE FOR ARTIFICIAL TEETH.

1,122,718.

Specification of Letters Patent.

Patented Dec. 29, 1914.

Application filed December 3, 1912, Serial No. 734,687. Renewed November 13, 1914. Serial No. 872,053.

To all whom it may concern:

Be it known that I, GUSTAV E. FRITZ, a citizen of the United States, residing at Peoria, in the county of Peoria and State of Illinois, have invented certain new and useful Improvements in Backing-Plates for Artificial Teeth, of which the following is a specification.

This invention has reference to an improved backing plate for interchangeable or detachable artificial teeth or facings, and a support, pin or tongue therefor, said support, pin or tongue being adapted to a slot or groove formed in said artificial tooth or facing.

One of the objects of the present invention is to provide a backing plate for an interchangeable or detachable artificial tooth or facing, preferably made of very thin and pliable metal, such for instance as gold or some similar material; said backing plate being adapted when applied to the tooth to be easily shaped to the posterior face thereof, the cervical border and as a protecting means for the bite or cutting edge.

A further object of the invention is to provide a preferably solid pin, supporting member or tongue adapted to a slot, groove or opening formed in a tooth or facing to which a backing plate may be secured; and a backing plate of very thin and pliable metal to which the pin, tongue or supporting member may be fixedly attached, said backing plate when applied to the tooth being adapted to be shaped thereto.

The invention has for a further object as an article of manufacture, a combined backing plate and pin, supporting member or tongue therefor; said backing plate being of very thin and pliable metal and said pin, supporting member or tongue arranged for connection with said backing plate by being riveted or otherwise suitably secured thereto. The object of making said backing plate of very thin and pliable metal is that when said pin, supporting member or tongue is inserted into the tooth or facing, should said pin, supporting member or tongue be too long, said backing plate may be bent back upon itself to enable the filing or cutting off of the supporting member or tongue to adapt it to a tooth or facing, whereby the backing plate may be shaped to said tooth or facing.

That the invention may be fully under-

stood reference is had to the accompanying drawing in which:

Figure 1 is a perspective view of a backing plate such as I use and to which the pin, supporting member or tongue may be attached; Fig. 2 is a perspective view of a pin, supporting member or tongue with means for attaching the backing plate thereto; Fig. 3 is a perspective view of a backing plate and the pin, supporting member or tongue attached thereto, the view showing that side 65 of the plate to which the body of the pin, supporting member or tongue is secured; Fig. 4 is a perspective view, similar to Fig. 3, with the exception that the opposite side of the backing plate is shown, with the securing means of the pin, supporting member or tongue projecting through the plate; Fig. 5 is a sectional view showing a backing plate and pin, supporting member or tongue attached, and applied to a tooth or facing, 75 the pin, or supporting member may be filed or cut off to adapt it to the length of the opening in the tooth and to permit the backing plate to be shaped to the tooth or facing; Fig. 6 is a sectional view similar to Fig. 5, 80 with the pin, supporting member or tongue fitting the slot or groove in the tooth or facing and the backing plate shaped to the posterior face, the cutting edge and the cervical border of the tooth, and Fig. 7 is a sectional 85 detail showing a pin, supporting member or tongue and a backing plate, illustrating a modified connection between the pin, supporting member or tongue and the backing plate.

Like characters of reference indicate corresponding parts throughout the figures.

I designates an interchangeable or detachable tooth or facing having the posterior face 2, the cervical border 3 and the beveled biting edge 4, so shaped to adapt a backing plate to form a protecting tip for the bite of said tooth or facing, and said tooth or facing is provided with a preferably dove-tailed slot or groove 5, extending into the 100 tooth or facing from the cervical border and terminating a suitable distance from the bite and opening out of the posterior face thereof.

The tooth or facing 1 is of well known 105 construction, and while I have shown the same provided with a preferably dove-tailed slot or groove to receive a like shaped pin,

supporting member or tongue, it is to be understood that the groove, opening or slot in the tooth may be round if desired or of some other suitable shape, and the pin, supporting member or tongue of contour to adapt itself thereto.

6 denotes a metal plate forming a backing for the tooth, said plate being preferably of very thin and pliable metal, such as gold or other suitable metal, but preferably gold. This plate may be made of any suitable size, preferably rectangular in shape, and provided with the plurality of openings 7, as shown in Fig. 1, or the single opening 8, as shown in Fig. 7.

9 denotes a pin, supporting member or tongue, in this instance, preferably wedge shaped, as shown, to adapt it to fit the correspondingly shaped groove or slot in the artificial tooth or facing. Said pin, supporting member or tongue 9 is provided with the plurality of lugs or projections 10, as shown in Fig. 2, or with the single lug or projection 11, shown in Fig. 7. I prefer that the lugs or projections 10, or the lug or projection 11 on the pin, supporting member or tongue 9 shall be located on the said pin, supporting member or tongue 9, nearest that end of the pin, supporting member or tongue which is inserted into the tooth or facing and lies adjacent to, or removed a short distance from the bite of the tooth or facing, see Fig. 5.

To assemble the plate 6 and the pin, supporting member or tongue 9 to produce the article of manufacture which I hereinafter claim, the lugs or projections 10 of the supporting member 9 are inserted through the openings 7 in the plate 6 and said lugs or projections 10 bent down in the manner shown at 12 in Fig. 4, for uniting and positively securing the said pin, supporting member or tongue 9 and the plate together. If the pin, supporting member or tongue 9 has only a single lug or projection 11, as shown in Fig. 7, said lug or projection is inserted through the opening 8 in the plate 6 and the opposite end portions 13 of said lug riveted down against the plate, in the manner shown in Fig. 7, for firmly uniting the supporting member and plate together.

I aim in the present article of manufacture to produce a backing plate and pin, supporting member or tongue which shall be adaptable to any tooth or facing having a groove, slot or opening into which the pin, supporting member or tongue may be inserted. The plate may be of any suitable size and the pin, supporting member or tongue of a length to adapt the same to various sizes of artificial teeth or facings, and in

the event of a dentist applying a pin, supporting member or tongue to a tooth, said pin, supporting member or tongue being longer than necessary or projecting without the cervical border of the tooth, as shown in Fig. 5, the plate may be bent back upon itself, as shown at 14, in Fig. 5, which will permit the dentist to file or cut off the projecting portion of the pin, supporting member or tongue to adapt it to the length of the groove, slot or opening in the tooth, as shown in Fig. 6, when the backing plate may be bent down and shaped to said tooth or facing, as shown. With the plate of the character specified, one that is thin enough and pliable enough to adapt it to a tooth or facing, said plate when applied to the tooth or facing may be very easily shaped to the posterior surface, cervical border, and the bite of the tooth, said biting edge if preferred, being beveled so as to provide a protecting tip of metal for the bite, and any surplus metal may be trimmed off of the plate to make a snug and neat fit on said tooth or facing.

In practice, in a great many cases, the dentist has great difficulty in providing and shaping a backing plate to a tooth or facing and in securing the supporting member thereto. I am aware, however, that a very stiff or rigid backing plate has been made having a supporting member secured thereto, said supporting member being hollow, but such backing plates must be bought in sizes to fit the particular tooth or facing to which they are to be attached. This is entirely obviated by the use of a backing plate such as I provide, to-wit, a backing plate that is adaptable to the tooth after being ground.

The advantage of the solid supporting member or tongue is, that it adds strength to the tooth, and filling the opening, slot or groove in the tooth as it does there is no chance for secretions lodging in the backing, which could be the case if the supporting member were hollow.

What I claim is:—

As an article of manufacture, a backing for an artificial tooth or facing, comprising a plate of pliable material, and a solid non-integral supporting member for entrance into a tooth attached thereto, said plate being pliable to make it adaptable to a tooth.

In testimony whereof I affix my signature in presence of two witnesses.

GUSTAV E. FRITZ.
